UNITED STATES PATENT OFFICE.

WILLIAM JOHN GEE, OF TULSE HILL, LONDON, ENGLAND.

METHOD OF AND APPARATUS FOR DRYING CHINA OR OTHER CLAY, FULLERS' EARTH, PIGMENTS, WHITING, AND THE LIKE.

1,274,158.

Specification of Letters Patent. Patented July 30, 1918.

Application filed April 6, 1915. Serial No. 19,599.

To all whom it may concern:

- Be it known that I, WILLIAM JOHN GEE, a subject of the King of England, residing at 48 Kingsmead road, Tulse Hill, London, England, have invented new and useful Improvements in Methods of and Apparatus for Drying China or other Clay, Fullers' Earth, Pigments, Whiting, and the like, of which the following is a specification.
- 10 This invention relates to an improved method of and apparatus for drying china or other clay, fullers' earth, pigments, whiting and like material, and more particularly to china-clay which has been washed and 15 precipitated or otherwise separated from the washing liquid and which contains an excess of moisture, the object of the present invention being to effect a rapid drying of the clay.
- 20 Heretofore it has been customary to dry the clay in thick layers in stationary troughs which are heated in order to drive off the excess moisture. Owing to the thickness of the clay this process however occupies a 25 considerable amount of time and involves considerable risk of burning the clay.
- According to the present invention the china-clay is dried in the form of very thin sheets or films which are subjected to intense heat while being moved. As these 30 layers are very thin and as they present a very large surface to the heat, the excess moisture is evaporated very quickly to the required degree. The clay is preferably pre-heated nearly to boiling point, and is thereafter slid over and in contact with a very 35 highly heated surface of a temperature of 300°-400° C. which will prevent the clay from sticking to the surface.
- 40 The china-clay is discharged from a narrow elongated slot of a hopper in the form of a thin sheet or film and is deposited on to a moving permeable band. This moving band is arranged endless around the stationary heating table, and consists of a series of longitudinal wires spaced sufficiently apart to allow the film of clay to sag and come into direct contact with the table, which is heated, by electricity, steam or by 45 other suitable means, to a point which prevents the clay sticking thereto. The table also supports the main weight of the film of clay, the longitudinal wires serving mainly for drawing the clay along the table and for 50 forming longitudinal recesses on the underside of the clay along which the steam may travel until it reaches a crack in the sheet of clay through which it passes into the lower chamber of a hood wherein it is collected and caused to preheat the clay. By 55 providing for the escape of the steam, the formation of blisters which might be caused by the shutting in of the steam between the drying surface and the clay is avoided.
- Any suitable means can be used for discharging the clay from the hopper. For instance the clay may be discharged by gravity, a stirring or expressing device being preferably provided near the outlet or outlets in order to facilitate the discharge of 60 the clay. The clay may also be discharged by pressure, and for this purpose a reciprocating piston may be arranged to work at the foot of the hopper and express the clay through a suitably shaped nozzle.
- The improved method is particularly suitable for drying china-clay containing about 65 45% by weight of moisture as the methods of drying china-clay at present in use are not satisfactory for treating a material of this 70 consistency and are generally employed in connection with a material having a larger percentage of water.
- The accompanying drawings illustrate by 75 way of example a machine for drying china-clay.
- Figure 1 is an elevation partly in section of the machine.
- Fig. 2 a plan partly in section.
- Fig. 3 is a section through the supply 80 hopper and
- Fig. 4 a detail view of the mechanism for actuating the stirring or expressing device.
- The material to be dried is supplied from a hopper *a* to an endless band *b* traveling 85 over a table *c*. The hopper is provided with a slot *d* and a stirring or expressing device consisting of an oscillating blade *e* pivoted at *f* close to the slot *d* and adapted to be oscillated from the continuously rotating shaft *g* by means of a crank and lever mechanism *h*, *i*, *k*, *l*. In order to regulate the 90 number of oscillations of the stirring device in accordance with the consistency of the material to be dried, step pulleys *m*, *n*, may be provided in the shaft *o* from which the 95 shaft *g* is driven. The endless band *b* consists of a number of parallel wires of nickel

or other non-oxidizing or harmlessly oxidizing metal passing over grooved pulleys *p* and *q* which are kept under sufficient tension by means of suitable tensioning devices such as springs *r* fixed at one end to the frame *s* of the machine and at the other end to levers *t* pivoted at their upper ends in the frame. These tensioning devices are in direct contact with the wires and will therefore 10 clean the wires before passing onto the table, and prevent tearing the sheet of clay by means of small particles of clay adhering thereto. Each wire is provided with a separate tensioning device. The wires slide over 15 the table *c* which is heated from below by any suitable means for instance by electric heaters *u*. The table is composed of a number of transverse members *y* made of ordinary channel iron covered with sheet aluminum. These members are placed close 20 together and form a practically uninterrupted flat surface which is very little liable to buckle under the influence of heat. Over practically the whole table *c* extends a hood 25 *z* which is divided by a partition into two chambers. The upper chamber communicates through pipes *z* with the suction ports of a centrifugal fan 1, the discharge ends of which communicate through a spreader 30 2 with the right end of the lower chamber. The hopper *a* is incased in a jacket *a'*, the lower end of which jacket is in communication with the outlet end of the lower chamber, the arrangement being such that the 35 clay within the hopper *a* is preheated by the waste heat from the hood. If desired the jacket may be incased with insulation as indicated at *a''*.

The operation of the machine is as follows:—The china-clay is delivered by the expressing device from the hopper *a* on to the endless band *b* in the form of a thin sheet, film or blanket. This sheet, film or blanket sags between the longitudinal wires *b* and 40 is supported mainly by the table *c*. The longitudinal wires *b* however slide the film over the heated table on which it is rapidly dried to the desired degree and from which it is discharged in the form of flakes. In order to utilize the heat as much as possible, air is drawn 45 through the upper chamber of the hood *z*. This chamber is heated by the steam arising from the drying of the material and also by radiated heat. The heated air thus obtained is then forced through the lower chamber over the material to be dried and is thereafter utilized together with the steam 50 evaporated by the drying process, for pre-heating the material to be dried in any desired manner or as indicated in Fig. 1. When 55 drying china-clay, it is advisable to preheat the material in the hopper almost to boiling point and to heat the table to a temperature of 300°—400° C. The heat, being produced 60 and utilized in comparatively small and

confined spaces, there is no difficulty in reducing the heat losses by effective heat insulation obtained by lagging.

Although temperatures exceeding 300° C. would "burn" china-clay, in this apparatus 70 there is no danger of "burning" as the speed of the band can be adjusted to remove the clay from the table with a water content of about 12½% which is the state in which china-clay is normally sold. 75

The particular construction of the endless band in the form of parallel wires has, *inter alia*, the advantage that the material to be dried is allowed to come more or less into contact with the heating table between two 80 adjacent wires so that a direct heat transmission is obtained in addition to the transmission by radiation. The wires constituting the endless band serve not only as means for moving the material over the table and 85 transmitting the heat of the table to the material but they serve also as means for the egress of the steam produced by the drying of the clay. This steam travels along the wires until it reaches a crack in the sheet 90 of clay through which it passes into the lower chamber of the hood. In this manner the formation of blisters is avoided, which might be caused by the shutting in of steam between the drying surface and the material 95 to be dried and would have a very unfavorable effect on the efficiency of the apparatus.

It will be understood that if the invention is to be applied to material other than china-clay the temperature employed will have to 100 be altered according to the nature of the material to be treated, the choice of the temperatures being governed on the one hand by the desire to dry the material as rapidly as possible and on the other hand by the 105 necessity of avoiding burning or otherwise spoiling the material.

I claim:

1. The method of drying china clay, fuller's earth, pigments, whiting, and material of like character, comprising the steps of continuously sliding the material in a thin sheet in plastic form through a heating device over a heated surface and in contact therewith to evaporate the moisture therefrom, substantially as described. 110

2. The method of drying china clay, fuller's earth, pigments, whiting, and material of like character, comprising the steps of feeding material in a thin sheet and in plastic form onto a heated surface and sliding said sheet over said surface, and passing a current of heated air over said sheet during its passage over the heated surface to carry off the moisture, substantially as described. 120

3. The method of drying china clay, fuller's earth, and material of a like character, comprising the steps of continuously sliding the material in a thin sheet and in plastic form through a heating device and over a 130

heated surface, and in contact therewith to evaporate the moisture therefrom and also forming conduits in the bottom of the sheet of clay during its passage through the drier 5 to permit the generated steam to pass off therethrough, substantially as described.

4. An apparatus for drying material, comprising a movable conveyer formed of a plurality of endless bands, a flat heating surface over which said bands are moved, and forming a support therefor, the space of the heating surface between the wires also forming a support for the material to be dried, means for moving said bands, means for heating said surface, and means for feeding a film of plastic material on the top of said bands to be carried over the heated surface thereby, substantially as described.

5. A drier, comprising a heated surface, means for heating said surface, a conveyer formed of a plurality of endless bands out of contact with each other arranged to move over said heated surface, means for moving said bands, a hood for said heated surface having a chamber therein arranged to be heated by the radiant heat from the heated surface, means for feeding a film of plastic material to be dried on said endless bands, said endless bands being arranged to move said film in a continuous manner over the heated surface, there being an air inlet to said heated chamber in the hood, and means for passing said heated air over the film during its passage over the heated surface 35 to carry off the moisture, substantially as described.

6. An apparatus for drying material, comprising a movable conveyer formed of a plurality of endless bands, a heating surface over which said bands are moved, and forming a support therefor, means for moving said bands, means for maintaining each band under tension, means for heating said surface, and means for feeding a film of plastic material on the top of said bands to be carried over the heated surface thereby, substantially as described.

7. An apparatus for drying material, com-

prising a movable conveyer formed of a plurality of endless bands, a heating surface over which said bands are moved, and forming a support therefor, means for moving said bands, means for heating said surface, a hopper for the material to be dried, and an expressing device within said hopper for feeding the material in film form to said bands, substantially as described.

8. An apparatus for drying material comprising a conveyer formed of a plurality of endless bands, a heating surface over which said bands are moved and forming a support therefor, means for moving said band, means for feeding a film of plastic material on the top of said bands to be carried over the heated surface, and independent means for maintaining each band under tension and for cleaning said bands while passing the tensioning devices, substantially as described.

9. A drier comprising a heated surface, means for heating said surface, a conveyer arranged to move over said heated surface, means for moving said conveyer, a hood for said heated surface having a chamber therein arranged to be heated by the radiant heat from the heated surface, a hopper having means for feeding a film of plastic material to be dried on said conveyer, said conveyer being arranged to move said film in a continuous manner over the heated surface, there being an air inlet to said heated chamber in the hood, means for passing said heated air over the film during its passage over the heated surface to carry off the moisture, and a jacket surrounding the hopper and arranged to receive the heated air and steam passing over the film to preheat the clay within the hopper, substantially as described.

In testimony whereof I have signed my name to this specification in the presence of two subscribing witnesses.
